Specification of Letters Patent. Patented Mar. 14, 1922.

Application filed March 26, 1921. Serial No. 455,802.

To all whom it may concern:

Be it known that I, FREDERICK SALATHE, a citizen of the United States, residing in Chicago, in the county of Cook and State 5 of Illinois, have invented a new and useful Improvement in Sludge Treatment Processes and Products, of which the following is a specification.

This invention relates to the treatment of 10 sludges, such for example as are obtained as residues from the acid treatment of crude oil lubricating stocks; important objects of the invention are to effect an efficient and substantially complete recovery from such 15 sludges of acid of a high degree of concentration, to recover also the reagent employed in separating the acid from the sludge, the recovered reagent being in a form so that it is available for further sludge treatment, 20 and to produce, in the carrying out of the improved sludge treatment process, a valuable hydrocarbon product having a wide range of industrial uses.

In addition to the general objects recited 25 above, the invention has for further objects such other improvements or advantages in operation and results as are found to obtain in the improved process and product hereinafter described or claimed.

30 In the accompanying drawings, forming a part of this specification and showing, for purposes of exemplification, a preferred form of apparatus in which the invention may be practiced, but without limiting the 35 claimed invention to such illustrative instance or instances:

Figures 1, 1^a and 1^b collectively illustrate a diagrammatic representation of apparatus for carrying out the improved sludge treat- 40 ment process of the present invention.

In its present embodiment, the invention is applied to the treatment of sludges obtained from crude oil lubricating stocks, and for convenience, the present description will 45 be confined to this use of the invention. The features of the invention are, however, susceptible of other valuable applications; consequently the scope of the invention is not confined to the specific use and specific 50 embodiment herein described as an illustrative example.

In the art of refining crude oils for the production of the various commercial products, a residue available as a lubricating

stock remains after the gasolines, kerosenes 55 and other light oils have been driven off. This lubricating stock, or the distillates therefrom, is usually subjected to a refining process in which it is treated with an acid, such as sulphuric acid, in an agitator. As a 60 result of the acid treatment of the lubricating stock, an acid tarry sludge is precipitated, which is separated from the refined oil. This acid sludge has a highly complex 65 composition and contains the sulphuric acid partially in a mechanical mixture with other constituents of the sludge and partially in the form of chemical combinations resulting from polymerization of the unsaturated hydrocarbons which must be eliminated from 70 the lubricating stock by the acid treatment. The composition of the sludge varies with the character of the crude oil from which the lubricating stock is derived, and is thus incapable of positive definition as to the entire 75 number or proportion of its constituent elements or compounds. However, such sludges contain, in addition to the acid, polymerized hydrocarbons, sulphonated hydrocarbons and oxidized hydrocarbons in an intimate mixture. The disposal of this sludge is a serious problem to the oil refiner, because of the acid character the sludge and its consequent destructive properties. Processes have been employed for the purpose 80 of recovering the unused acid which is mechanically held in the sludge. These processes contemplate subjecting the sludge to a water wash to such an extent that the tarry matters contained in the sludge are 85 floated out, after which the acid is allowed to settle out by gravity. The separation of the acid from the water is then effected by a decanting process. Such water wash treatment of acid sludges, for the recovery 90 of the acid is, however, open to the serious disadvantage, that the acid recovered is of necessity greatly diluted by the water used in the sludge treatment. The acid usually recovered is therefore quite dilute, having, 100 at best, a specific gravity of only about 30° Bé. to 35° Bé. Moreover, the water wash treatment is ineffective with many sludges, as they emulsify with water; that is to say, the tarry compounds in many sludges are of 105 such a nature that when the acid is diluted with the water wash, a murky emulsion is formed from which no acid can be separated,

and which is practically valueless for further industrial use. Even in the case of sludges which do not have this tendency to emulsify completely, the separated tarry 5 compounds will always retain a percentage of acid water which is not only difficult to remove but forms other compounds, by hydrolysis with some of the hydrocarbon constituents of the sludge.

10 The present invention comprehends the treatment of sludges, such as mentioned above, by an improved process which removes substantially the entire content of acid from the sludge and effects the immediate 15 recovery of the acid in a highly concentrated form, as contradistinguished from the acid of low concentration obtained by former processes and also produces a valuable product capable of wide industrial use, and 20 of especial utility as a constituent of lacquers or paints, or for employment as a roofing material. Referring to the drawings which illustrate an embodiment of apparatus for carrying out the improved process of the invention 25 and for obtaining the new product hereinafter described, there is shown at 11 an agitator of the usual type employed for the acid refining treatment of crude oil lubricating stocks, or their distillates. A quantity 30 of lubricating stock, for example, is charged into the agitator 11 and is therein subjected to air agitation with from 1 to 10 percentum of sulphuric acid by weight, the acid being commonly of about 66° Bé., although to obtain 35 oils of very light color or completely white, stronger acid may be employed. The acid used in the agitator 11 may conveniently be supplied from an acid tank 12 having an acid line connection 13 with an acid 40 egg 14, from which the acid may be pumped in the usual manner through an acid line 45 to the agitator 11.

After the agitation of the lubricating stock or lubricating distillates and acid has progressed for about 30 to 40 minutes in the air agitator 11, the agitation is discontinued and the contents of the agitator are allowed to stand for about three hours. Lubricating stocks include reduced lubricating oil left 50 as residue in the still. The air employed in the agitation process exerts a slight oxidizing effect on the mixture and the oxidized products are taken up by the sludge.

When the settling period has been completed, the refined oil is drawn off from the top of the settled mixture and the acid sludge which settles out in the bottom of the agitator may be drawn off through a valve controlled sludge pipe 16 into sludge 55 buckets 17 carried by a crane hoist 18 and having provision for swinging the filled sludge buckets 17 over and dumping their contents into a mixer 19.

The mixer 19 is preferably of the mechanical type, in which agitation of the material

deposited in the mixer is effected by means of paddles 20 secured to a vertical shaft 21. This shaft 21 may be driven by suitable driving and power connections indicated generally at 22. In accordance with the invention, the sludge discharged into the mixer from the sludge buckets 17 is thoroughly agitated with a hydrocarbon solvent, of the aromatic hydrocarbon series, preferably in equal proportion by volume with the sludge 75 deposited in the mixer. Solvent naphtha, a product from the coal tar distillation, is a satisfactory solvent for this purpose, and, in fact, it is preferable to employ a solvent naphtha, the boiling point of which ranges 80 between 250° F. and 400° F. However, the invention is not limited to the particular hydrocarbon solvent herein mentioned, nor to solvent naphtha within the above stipulated range of boiling points, since other solvents, 85 including naphthas having different boiling points may be employed. The solvent is supplied to the mixer 19 from a solvent line 23.

The agitation of the sludge and solvent 90 is continued in the mixer 19 until substantially the entire quantity of the hydrocarbon constituents of the sludge are in solution. Ordinarily this will require an agitation of about two hours for average sludges. As 95 soon as the sludge solution has been obtained, the agitation is discontinued by disconnecting the power from the paddles 20 and the sludge solution is allowed to stand until the acid settles out in the bottom of the mixer, 100 the settling usually requiring about two hours.

As soon as the acid has settled out, it may be drawn off through a valve controlled acid line 24 into an acid tank 25, in which the 105 recovered acid may be stored for future use. By the employment of the hydrocarbon solvent, practically the entire quantity of acid in the acid sludge originally deposited in the mixer is recovered from the sludge solution. 110 Moreover, because of the fact that no water is employed in effecting the recovery of the acid, the recovered acid is of a high degree of concentration, approximating that of the acid employed for refining the lubricating 115 stock in the agitator 11. For example, if the acid employed in the agitator 11 have a specific gravity of about 66° Bé., the acid recovered from the sludge solution shows little loss of concentration, ranging from 57° to 120 60° Bé., or even a higher degree of concentration. This highly concentrated recovered acid may be readily further concentrated for use in the refining operation above described. In cases where the acid initially employed in the refining operation is of a higher degree of concentration, the recovered acid will 125 show a like increase in concentration.

After the acid has been recovered from the sludge solution, the solution may be then 130

- neutralized by titrating with the neutralizing agent. A solution of soda ash (sodium-carbonate or sodium hydrate), containing about four ounces of salt to one or two pints 5 of water usually will be sufficient for removing the residual acidity in the sludge solution contained in an agitator having a capacity of about two-hundred gallons. The neutralizing solution is supplied from a neutralizing solution egg 25 having a supply line connection 26 with the mixer. When the neutralized solution has settled out in the bottom of the mixer 19, the waste solution is drawn off through a valve controlled waste 10 solution line 27.
- The sludge solution left in the mixer is then discharged through a valve controlled sludge solution line 28 and pumped by a pump 29 into a still 30. The still 30 is provided with an external fire box 31 located beneath the still and in a heating chamber 32 which connects with a stack 33. Above the fire box 31 is a steam coil 34 adapted to be supplied with live steam from a supply-line 20 35 and having a valve controlled supply connection 36 with a steam manifold 37 located in the bottom of the still. The manifold 37 is provided with a plurality of branch pipes 38, each of which has steam jets, for permitting the steam to circulate through the solution in the chamber of the still 30. When the desired quantity of sludge solution has been delivered to the still 30, the temperature is first raised rapidly by direct firing to 35 about 250° F., during which time the lighter portions of the solvent in the solution are distilling over and passing out through a solvent discharge line 39 into a condenser 40. Live steam is then introduced into the coil 40 34 and is permitted to discharge from the branch pipes 38 of the manifold 37 and to circulate through the solution within the still. The firing is continued until all of the solvent has been distilled off, the final temperature necessary for complete removal of 45 the solvent depending upon the solvent used. The recovered solvent condenses in the condenser 40 and next passes through a separator 41 in which the solvent is separated from the water condensed from the steam. From 50 the separator 41 the solvent passes through a solvent line 42 to a solvent tank 43, from which the recovered solvent may be pumped by a pump 44 through a return line 45 that 55 delivers the solvent to a preheater 46 having a discharge connection 47 with a pump 48. The pump 48 delivers the solvent into the supply line 23 leading to the mixer 19 in which the recovered solvent may be used for 60 further solution treatment of the sludge deposited in the mixer. The solvent recovered by the process of the invention is in exceedingly pure form, and where solvent naphtha is employed in the original solution process 65 in the mixer 19, a high grade white naphtha is obtained in the solvent tank 43, because of the action of the acid with which the solvent is brought into contact in the mixer. Moreover, practically all of the solvent is recovered from the sludge solution, there being 70 but a small percentage of loss of solvent.
- After the distillation of the solvent in the still 30 has been completed, the still is allowed to cool off and the residue is discharged through a valve controlled discharge line 49 and deposited in containers 50 on a turntable 51. This residue from the still is an exceedingly valuable product. It contains sulphonated hydrocarbons, polymerized hydrocarbons and oxidized hydrocarbons all in an intimate admixture, and is practically free from hydrolyzed hydrocarbons. The residue is further characterized by the fact that it contains substantially the entire quantity of sulphonated hydrocarbons 80 present in the original sludge, there being no water wash to eliminate any sulphonated hydrocarbons. There is no emulsification of any of the polymerized hydrocarbons in the residue. The relatively large quantity of 85 sulphonated hydrocarbons present in the residue as compared with the residues obtained from water wash treatment of sludges give a rubbery and adhesive quality to the residue which makes it valuable as a roofing 90 or an adhesive material. It may also be employed as an ingredient of paints, varnishes or lacquers. The residue is usually quite black in color, solid at ordinary temperatures, plastic in its nature, and of great adhesive power. It is practically waterproof. A further characteristic of the residue obtained by the process of the present invention is that it is almost entirely soluble in 95 gasoline of 60° Bé., for example, of approximately 97% solubility, whereas residues obtained from water wash treatment of sludges at best only give about 75% solubility in gasoline of like specific gravity; the sludge obtained by the present process moreover 100 shows an iodine value of 25 to 29 whereas residues obtained from water wash sludges 105 show only an iodine value of 8.
- The invention as hereinabove set forth may be variously embodied within the scope 110 of the claims hereinafter made.
- I claim:
1. In a process of treating acid sludges obtained from crude oils, the combination of steps that consists in: mixing and agitating a proportion of such sludge with a substantially equal proportion of hydrocarbon solvent to liberate acid having a specific gravity of about 50° to 60° Baumé; then allowing the acid to settle out from the mixture and recovering such acid; then mixing a neutralizing agent with the sludge solution to neutralize the residual acidity; then removing the neutralizing agent from the sludge solution; and then subjecting the 115

sludge solution to distillation to recover the hydrocarbon solvent and to obtain a hydrocarbon residue containing polymerized hydrocarbons, sulphonated hydrocarbons and 5 oxidized hydrocarbons, which residue is characterized by an adhesive quality and is plastic in its nature at ordinary atmospheric temperatures; substantially as specified.

10 2. In a process of treating acid sludges obtained from crude oils, the combination of steps that consists in: mixing and agitating a proportion of such sludge with a substantially equal proportion of solvent 15 naphtha to liberate acid having a specific gravity of about 50° to 60° Baumé; then allowing the acid to settle out from the mixture and recovering such acid; then mixing a neutralizing agent with the sludge solution to neutralize the residual acidity; then removing the neutralizing agent from the sludge solution; and then subjecting the sludge solution to distillation to recover the solvent naphtha and to obtain a hydrocarbon residue containing polymerized hydrocarbons, sulphonated hydrocarbons and oxidized hydrocarbons; substantially as specified.

30 3. In a process of treating acid sludges obtained from crude oils, the combination of steps that consists in: mixing and agitating such sludges with solvent naphtha to liberate the acid; then allowing the acid to settle out from the mixture and recovering such acid; then mixing a neutralizing agent with the sludge solution to neutralize the residual acidity; then removing the neutralizing agent from the sludge solution; and then subjecting the sludge solution to 35 distillation to recover the solvent naphtha and to obtain a hydrocarbon residue containing polymerized hydrocarbons, sulphonated hydrocarbons and oxidized hydrocarbons; substantially as specified.

45 4. In a process of treating acid sludges obtained from crude oils, the combination of steps that consists in: mixing such sludges with a hydrocarbon solvent to liberate the acid; then allowing the acid to settle out from the mixture and recovering such acid; then mixing a neutralizing agent with the sludge solution to neutralize the residual acidity; then removing the neutralizing agent from the sludge solution; and then subjecting the sludge solution to distillation to recover the hydrocarbon solvent and to obtain a hydrocarbon residue containing polymerized hydrocarbons, sulphonated hydrocarbons and oxidized hydrocarbons, substantially as specified.

50 5. In a process of treating acid sludges obtained from crude oils, the acid in said sludges being of a specific gravity of not less than 50° Baumé, the combination of 55 steps that consists in: mixing such sludges

with a hydrocarbon solvent to liberate the acid without substantial dilution thereof; then allowing the acid to settle out from the mixture and recovering such acid; and then subjecting the sludge solution to distillation to recover the hydrocarbon solvent and to obtain a hydrocarbon residue containing polymerized hydrocarbons, sulphonated hydrocarbons and oxidized hydrocarbons; substantially as specified.

60 6. In a process of treating acid sludges obtained from crude oils, the combination of steps that consists in: mixing and agitating a proportion of such sludge with a substantially equal proportion of hydrocarbon solvent to liberate acid having a specific gravity of about 50° to 60° Baumé; then allowing the acid to settle out from the mixture and recovering such acid; and then subjecting the sludge solution to distillation to recover the hydrocarbon solvent and to obtain a hydrocarbon residue containing polymerized hydrocarbons, sulphonated hydrocarbons and oxidized hydrocarbons; substantially as specified.

65 7. In a process of treating acid sludges obtained from crude oils, the combination of steps that consists in: mixing and agitating a proportion of such sludge with a substantially equal proportion of solvent naphtha to liberate acid having a specific gravity of about 50° to 60° Baumé; then allowing the acid to settle out from the mixture and recovering such acid; then subjecting the sludge solution to distillation to recover the solvent naphtha and obtain a hydrocarbon residue containing polymerized hydrocarbons, sulphonated hydrocarbons and oxidized hydrocarbons; substantially as specified.

70 8. In a process of treating acid sludges obtained from crude oils, the combination of steps that consists in: mixing and agitating such sludges with solvent naphtha to liberate the acid; then allowing the acid to settle out from the mixture and recovering such acid; and then subjecting the sludge solution to distillation to recover the solvent naphtha and obtain a hydrocarbon residue containing polymerized hydrocarbons, sulphonated hydrocarbons and oxidized hydrocarbons; substantially as specified.

75 9. In a process of treating acid sludges obtained from crude oils, the combination of steps that consists in: mixing such sludges with a hydrocarbon solvent to liberate the acid; then allowing the acid to settle out from the mixture and recovering such acid; and then subjecting the sludge solution to distillation to recover the hydrocarbon solvent and to obtain a hydrocarbon residue containing polymerized hydrocarbons, sulphonated hydrocarbons and oxidized hydrocarbons; substantially as specified.

- acid from acid sludges obtained from crude oils, as hereinabove described, which consists in mixing and agitating a proportion of such sludge with a substantially equal proportion of solvent naphtha to liberate sulphuric acid having a specific gravity of about 50° to 60° Baumé; and then effecting a gravity separation of the acid from the sludge solution.
- 10 11. The process of recovering sulphuric acid from acid sludges obtained from crude oils, as hereinabove described, which consists in mixing and agitating a proportion of such sludge with a substantially equal proportion of solvent naphtha and thereby recovering from the sludge sulphuric acid having a specific gravity of about 50° to 60° Baumé.
12. The process of recovering sulphuric acid from acid sludges obtained from crude oils, as hereinabove described, which consists in mixing and agitating a proportion of such sludge with a substantially equal proportion of hydrocarbon solvent and thereby recovering from the sludge sulphuric acid having a specific gravity of about 50° to 60° Baumé.
13. The process of recovering sulphuric acid from acid sludges obtained from crude oils, as hereinabove described, which consists in mixing a proportion of such sludge with solvent naphtha and thereby recovering from the sludge sulphuric acid.
14. The process of recovering sulphuric acid from acid sludges obtained from crude oils, the acid in said sludges being of a specific gravity of not less than 50° Baumé as hereinabove described, which consists in mixing a proportion of such sludge with hydrocarbon solvent and thereby recovering from the sludge the sulphuric acid without substantial dilution thereof.
15. The process of recovering sulphuric acid from acid sludges obtained from crude oils, as hereinabove described, which consists in subjecting such sludges to treatment by a hydrocarbon solvent and by such solvent treatment effecting the recovery from the sludge of the sulphuric acid.
16. The process of recovering acid from acid sludges obtained from crude oils, as hereinabove described, which consists in subjecting such sludges to treatment by a hydrocarbon solvent and by such solvent treatment recovering the acid from such sludges.
17. The process of recovering acid from acid sludges obtained from crude oils, as hereinabove described, which consists in subjecting such sludges to treatment by solvent naphtha and by such solvent treatment recovering the acid from such sludges.
18. The solid hydrocarbon product obtained from the solvent treatment of acid crude oil sludges, which product contains polymerized hydrocarbons, sulphonated hydrocarbons and oxidized hydrocarbons, and is characterized by a plastic and adhesive nature, an absence of hydrolyzed bodies, a substantially complete solubility in gasoline of 60° Baumé and an iodine value of substantially 27.
19. The solid hydrocarbon product containing polymerized hydrocarbons, sulphonated hydrocarbons and oxidized hydrocarbons, and characterized by a plastic and adhesive nature, an absence of hydrolyzed bodies, a substantially complete solubility in gasoline of 60° Baumé and an iodine value of substantially 27.
20. The solid hydrocarbon product containing polymerized hydrocarbons, sulphonated hydrocarbons and oxidized hydrocarbons, and characterized by an absence of hydrolyzed bodies, and a substantially complete solubility in gasoline of 60° Baumé.
21. The solid hydrocarbon product containing polymerized hydrocarbons, sulphonated hydrocarbons and oxidized hydrocarbons, and characterized by an absence of hydrolyzed bodies.

FREDERICK SALATHE.
